UNITED STATES PATENT OFFICE.

LEWIS MILLER, OF OIL CITY, PENNSYLVANIA, ASSIGNOR OF ONE-HALF OF HIS RIGHT TO ALBERT WILLIAM KRAMER, OF SAME PLACE.

WAGON-JACK.

SPECIFICATION forming part of Letters Patent No. 224,461, dated February 10, 1880.
Application filed October 14, 1879.

To all whom it may concern:

Be it known that I, LEWIS MILLER, of Oil City, in the county of Venango and State of Pennsylvania, have invented new and useful 5 Improvements in Wagon-Jacks, of which the following is a specification.

My invention relates to that class of jacks which are made with a notched elevating bar to rest on the ground at one end and joined 10 at the other end to a fulcrum-bar through the medium of an operating-lever, by the movement of which the notched bar, which, in use, is placed beneath the axle to be lifted, is raised or lowered, as required.

15 My improvement particularly consists in the construction of an elbow-lever, as herein-after described, forked to embrace the ends of the fulcrum-bar and notched elevating-bar respectively, and having a socket for the reception of a handle; also, in the combination of the aforesaid socketed elbow-lever with a notched elevating-bar and a fulcrum-bar, as hereinafter described.

20 In the accompanying drawings, Figure 1 is a side elevation of the jack with the notched bar lowered. Fig. 2 is a side elevation with the said bar elevated. Fig. 3 is a perspective view of the forked and socketed elbow-lever detached. Fig. 4 is a side view of the jack 25 packed for transportation or storage.

30 A represents the lifting-bar, constructed with any desirable number of steps or notches, a a a, on either one of which the axle of a wagon or other vehicle may rest. B is a fulcrum-bar.

35 C represents my improved elbow-lever, constructed with two cheek-plates or forks, c c, the extremities of which are pivoted to the upper end of the notched bar A, and the central 40 elbow portions to the extremity of the fulcrum-bar B. The free end of the double or forked elbow-lever is provided with a socket, c', for

the reception of a handle, D, which will thus be placed in position when the jack is to be used, or may be removed when it is desired to 45 pack the entire jack in a small compass for transportation or storage, as illustrated in Fig. 4.

My invention constitutes a valuable improvement in the class of jacks referred to, in 50 that it combines extreme simplicity in construction and operation with great strength and durability, as well as convenience in use.

55 In operation, the jack being in the position shown in Fig. 1, the notched bar A is inserted until the proper step a engages beneath the axle. The hand-lever D being then drawn down, the elbow-joint C is thrown into the position shown in Fig. 2, causing the arms which connect the ends of the bars A B to pass a 60 little beyond a vertical position, and thus afford secure support, after the manner usual with jacks of this class.

65 The bars A, B, and D are constructed of wood, and the connecting elbow-lever or joint-piece C of metal, preferably of malleable iron.

I am aware that lifting-jacks have been constructed with notched supporting-bars pivoted to the ends of levers mounted on suitable frames. This construction, therefore, I do not 70 claim.

Having thus described my invention, the following is what I claim as new therein and desire to secure by Letters Patent:

75 The connecting-iron C, constructed with two elbow branches, c c, and a socket, c', in combination with a notched bar, A, fulcrum-bar B, and handle D, substantially as shown and described.

LEWIS MILLER.
